UNITED STATES PATENT OFFICE.

ERNEST H. SHAFF, OF GRAND HAVEN, MICHIGAN, ASSIGNOR TO WILLIAM H. KELLER INC., OF GRAND HAVEN, MICHIGAN, A CORPORATION OF MICHIGAN.

FLUID-PRESSURE MOTOR.

Application filed April 2, 1923. Serial No. 629,263.

To all whom it may concern:

Be it known that I, ERNEST H. SHAFF, a citizen of the United States, and a resident of Grand Haven, county of Ottawa, State of Michigan, have invented an Improvement in Fluid-Pressure Motors, of which the following description, in connection with the accompanying drawings, is a specification, like characters on the drawings representing like parts.

My invention relates to fluid pressure motors, and particularly but not exclusively to that type of impact tool known as a pneumatic hammer.

My invention will be best understood from the following description when read in the light of the accompanying drawings of an example of my invention selected for illustrative purposes, while the scope of my invention will be more particularly pointed out in the appended claims.

In the drawings:—

Fig. 1 shows an elevation of a pneumatic hammer constructed according to my invention and with parts in section;

Figs. 2 and 3 are longitudinal sections of the pneumatic hammer according to Fig. 1 and showing the valve in different positions. In Figs. 2 and 3 for convenience of illustration the ports and passages as far as possible are moved into the same plane, the true position and number of ports and passages being indicated by

Fig. 4 which is a section of the pneumatic hammer on the line 4—4 of Fig. 3.

Referring to the drawings and to the preferred embodiment of my invention I have shown a pneumatic hammer having a barrel 1 in the bore 3 of which reciprocates the hammer piston 5, the latter being arranged to strike at the end of its forward stroke the rear end of the shank 7 of a rivet set received by and closing the enlarged front end of the bore 3.

The rearward portion of the barrel 1 is enlarged exteriorly as is indicated at 9, this portion being recessed to provide a socket 11, while its extreme end is exteriorly screw threaded as indicated at 13. The socket 11

receives the forward valve cage section 15 and the rearward valve cage section 17, the valve cage so formed having a bore which forms a prolongation of the bore 3 and receives the tubular valve 19 which interiorly is of such diameter that the hammer piston 5 can enter it.

For supporting the tool I herein provide a grasping handle 21 which has integrally formed therewith the sleeve 23, the latter being interiorly screw threaded and received upon the screw threads 13 of the barrel. The base 25 of the grasping handle forms the rear cylinder head of the pneumatic hammer and abuts the rearward end of the valve cage section 17 so that when the handle is screwed into position on the barrel the parts will be held in assembled relation.

Pressure motive fluid, hereinafter termed air, is admitted to the machine by way of a hose, not shown, which is connected to the nipple 27 on the grasping handle. Formed through the grasping handle is a passage 29 which, as will be understood, is placed in communication with the nipple 27 and leads to a chamber 31 in the base 25 of the grasping handle.

As illustrated, for admitting air to the rearward end of the bore 3, the chamber 31 in the base of the grasping handle has in communication therewith a plurality of passages 33 which extend through the valve cage section 17 and are connected by radial passages 35 with the interior bore of said section said radial passages opening into said bore through ports positioned to be opened and closed by the valve 19.

For exhausting the rearward end of the bore 3 in the present embodiment of my invention the forward end of the valve controls a series of radial passages 37, each of which is in communication with a corresponding passage 39 leading through the walls of the barrel and valve cage section 15 to the atmosphere from an annular groove 41 formed in the enlargement 45 of the bore 95 of said valve cage section.

The enlargement 45 of the bore of the valve cage section 15 is aligned and com-

municates with the smaller enlargement 47 of the bore of the valve cage section 17, and leading from the groove 48 at the rearmost end of the enlargement 45 is a passage 49 formed in the walls of the valve cage section 15 and the cylinder and opening into the bore 3 adjacent the rearward end of the shank of the rivet set. Leading from one of the passages 33 to the enlargement 47 is a somewhat restricted passage 51. Herein for alternately connecting the passage 49 to the passages 39 and 51 so as to admit and exhaust air to and from the front end of the bore 3 and for purposes hereinafter set forth the forward portion of the valve is provided with the annular exterior flanges 53 and 55 which fit the enlargement 45, while the rearward portion of the valve is provided with a pair of annular flanges 57 and 59 which fit the enlargement 47.

The operation of the device so far described is as follows. With the parts in the position shown by Fig. 2 motive fluid passes from the passage 29 into the chamber 31 and hence to the rearward end of the bore 3 by way of the passages 33 and 35, the latter in this position of parts being uncovered by the rearward end of the valve. This causes the piston to travel forwardly, the air in front of the piston exhausting through the passage 49 to the atmosphere by way of the chamber 61 between the valve flanges 55 and 57 and the passages 39. When the piston reaches the front end of the bore 3 the valve by means hereinafter to be described shifts to the position shown by Fig. 3 which causes the rearward end of the valve to close the ports 35 and consequently stop the admission to the rearward end of the bore 3. It also interrupts the communication between the passages 39 and 49 and places the passage 49 in communication with the passage 51 and at the same time the front end of the valve uncovers the ports 37. This admits motive fluid to the front end of the cylinder by way of the passage 29, the chamber 31, the passage 33 shown at the bottom of Fig. 3, the passage 51, the chamber 61 and the passage 49, and in consequence the hammer moves rearwardly, the air at the rearward side of the hammer passing to the atmosphere by way of the passages 37 and 39.

For shifting the valve rearwardly I herein provide the wall of the barrel with one or more passages 63 which open into the bore 3 through a port or ports 65 positioned to be uncovered by the rearward end of the hammer when the same travels forwardly, the passage or passages 63 communicating with the chamber 67 in front of the valve flange 53 by way of a somewhat restricted passage 66. When the forwardly traveling hammer uncovers the port or ports 65 air is admitted from the bore 3 to the chamber 67 and this

air acting on the forward side of the flange 53 overcomes the pressure of the air in the chamber 68 acting upon the rearward side of the flange 59 and in consequence rearward movement of the valve is initiated. As shown in Fig. 3 I form in the walls of the valve cage sections a passage 69 of relatively large volume which passage is supplied with air by a restricted passage 71 in communication with one of the ports 33. Leading from the passage 69 to the chamber 67 is a narrow slot 73 which is positioned to be closed by the flange 53 when the valve is in its forward position and to be uncovered by said flange when the valve is in its rearward position. In consequence when rearward motion of the valve is initiated by air passing through the port or ports 65 and passages 63 and 66 to the chamber 67 the flange 53 uncovers the slot 73 to admit additional air to the chamber 67. It will be noted that when the piston is in the position shown in Figs. 2 and 3 and the valve shifts from the position shown in Fig. 2 to the position shown in Fig. 3 the chamber 67 will be vented to the atmosphere by way of the passage 63 and the bore 3 because the front end of the valve then uncovers the passages 37 which connect the bore 3 to the atmosphere. The air admitted to the chamber 67 through the slot 73 is effective to maintain enough pressure in the chamber 67 after the passages 37 are opened to exert considerable force for holding the valve in its rearward position. As the piston moves rearwardly the pressure in the chamber 67 increases momentarily during the transit of the piston over the port 65, and when the front end of the piston again uncovers the port 65 the pressure in the chamber 67 drops slightly owing to the somewhat low pressure conditions in the front of the bore 3 existing at this time by reason of wire drawing through the passage 51.

In Fig. 2 I have shown in communication with the chamber 68 behind the valve flange 59 a radial passage 77 which connects with the rearward end of a passage 79, the passage 79 being placed in communication with one of the passages 33 by a passage 81 of smaller diameter than said passage 79. The passage 79 opens into the end of the passage 85, and the latter into the end of the passage 85, the passages 79, 83 and 85 in the order enumerated being of progressively increasing diameter. The passage 85 opens into the bore 3 in the valve cage section 15 just forwardly of the front end of the valve 19. When the valve is in its rearward position as indicated by Fig. 3 the air which passes through the passage 81 exhausts to the atmosphere by way of the passages 79, 83 and 85, the bore 3, and the passages 37 and 39. The arrangement of passages just described

- forms an ejector, the air passing through the passage 81 entering the passage 79 in the form of a jet which creates suction in the passage 77 and chamber 68, and the reduced pressure caused by this suction in conjunction with the pressure in the chamber 67 acts to hold the valve in its rearward position against the effect of the pressure in the chamber 61.
- 10 In the present construction when the piston travels rearwardly it interrupts communication between the passage 85 and the bore 3. This will effect forward movement of the valve, for when this occurs air cannot escape from the passage 85 to the atmosphere, and consequently the ejector effect above described is destroyed, pressure then building up in the chamber 68 because the passage 81 is still connected to the live air supply. The building up of pressure in the chamber 68 under these conditions exerts enough force aided by the pressure in the chamber 61 to overcome the pressure in the chamber 67, and in consequence the valve 20 moves forward, which relieves the chamber 67 of pressure because the forward movement of the valve closes the slot 73 and connects the port 65 to the atmosphere by way of the bore of the cylinder, passage 49, chamber 61 and passages 39.
- Although I have described for purposes of illustration one specific embodiment of my invention it is to be understood that I am not limited thereto, but that within the 35 scope of my invention wide deviations may be made therefrom without departing from the spirit of my invention.
- Claims.
1. A pneumatic hammer having in combination a cylinder, a hammer piston, a valve; means providing an ejector having a nozzle, a suction orifice and a combining tube; said nozzle being permanently open to the source of motive fluid supply to the 40 machine, said suction orifice permanently communicating with a rearwardly facing pressure surface of said valve, said combining tube opening into said cylinder, an exhaust passage for one end of said cylinder, and said piston intermittently interrupting the communication between said combining tube and cylinder.
2. A pneumatic hammer having in combination a cylinder, a hammer piston, a valve 45 for controlling said hammer having a working pressure surface, and means including fluid conduits controlled by said hammer piston for alternately subjecting said working pressure surface to positive fluid pressure and to suction.
3. A pneumatic hammer having in combination a cylinder, a hammer piston, a valve for controlling said hammer piston, said valve having a working pressure surface, and means including fluid conduits for alternately subjecting said working pressure surface to positive fluid pressure and to suction.
4. A pneumatic hammer having in combination a plurality of movable members 50 one of which serves as a hammer piston and another as a valve, said valve controlling said hammer piston and having a pressure surface, and means including fluid conduits controlled by the movement of one of said members for alternately subjecting said pressure surface to positive pressure and to suction.
5. A pneumatic hammer having in combination a cylinder, a hammer, a valve, 55 means providing an ejector having a discharge conduit communicating with the atmosphere by way of the hammer chamber of said cylinder, means for intermittently interrupting such communication, and said valve having a working pressure surface acted upon by gaseous fluid the degree of pressure of which is controlled by said ejector.
6. A pneumatic hammer having in combination a cylinder, a hammer, a valve, 60 means providing an ejector cooperating with said valve, and means for alternately opening and closing the discharge conduit of said ejector.
7. A pneumatic hammer having in combination a cylinder, a hammer, a valve having a working pressure surface, means providing an ejector discharging into said cylinder and arranged for creating suction on 65 said working pressure surface, an exhaust passage for said cylinder controlled by said valve, and said hammer controlling the discharge of said ejector into said cylinder.
8. A pneumatic hammer having in combination a cylinder, a hammer, a valve for controlling said hammer, an exhaust port for said cylinder controlled by said valve, means controlled by said hammer for shifting said valve for opening said exhaust port, an ejector discharging into the atmosphere by way of said cylinder and said exhaust port, said ejector creating suction for holding said valve after it is shifted, and said hammer interrupting the discharge of said ejector 70 when said valve is again to be shifted.
9. A pneumatic hammer having in combination a cylinder, a hammer, a valve, said valve having a working pressure surface effective to move the valve in one direction and a working pressure surface of different area effective to move the valve in an opposite direction, means for admitting motive fluid to said first surface, means providing an ejector for creating suction on said second mentioned area, and means for interrupting the discharge from said ejector for causing the building up of pressure on said second mentioned area.
10. A pneumatic hammer having in com- 75

bination a cylinder, a hammer, a valve, said valve having a working pressure surface effective to move the valve in one direction and a working pressure surface of different area effective to move the valve in an opposite direction, means controlled by said hammer for intermittently admitting motive fluid to said first surface, means providing an ejector for creating suction on said second mentioned area, and means for interrupting the discharge from said ejector for causing the building up of pressure on said second mentioned area.

11. A pneumatic hammer having in combination a cylinder, a hammer, a valve, said valve having a working pressure surface effective to move the valve in one direction and a working pressure surface of different area effective to move the valve in an opposite direction, a port positioned to be overrun by said piston for causing pressure fluid to act on said first mentioned surface for shifting said valve, and means providing an ejector for creating suction on said second mentioned surface, and said ejector discharging into said cylinder.

12. A pneumatic hammer having in combination a cylinder, a hammer, a valve, said valve having a working pressure surface effective to move the valve in one direction and a working pressure surface of different area effective to move the valve in an opposite direction, an exhaust passage controlled by said valve, a port positioned to be overrun by said hammer for causing actuating fluid to flow from said cylinder and act on said first mentioned surface whereby to cause said valve to shift and open said exhaust passage, and means providing an ejector discharging into said cylinder for creating suction on said second mentioned surface of said valve when said exhaust passage is open.

13. A pneumatic hammer having in combination a cylinder, a hammer, a valve, said valve having a working pressure surface effective to move the valve in one direction and a working pressure surface of different area effective to move the valve in an opposite direction, an exhaust passage controlled by said valve, a port positioned to be overrun by said hammer for causing actuating fluid to flow from said cylinder and act on said first mentioned surface whereby to cause said valve to shift and open said exhaust passage, means providing an ejector discharging into said cylinder for creating suction on said second mentioned surface of said valve when said exhaust passage is open, and said ejector being supplied with motive fluid for subjecting said second mentioned surface to positive pressure when said exhaust passage is closed.

14. A pneumatic hammer having in combination a cylinder, a hammer, a valve, said

valve having a working pressure surface effective to move the valve in one direction and a working pressure surface of different area effective to move the valve in an opposite direction, an exhaust passage controlled by said valve, a port positioned to be overrun by said hammer for causing actuating fluid to flow from said cylinder and act on said first mentioned surface for causing said valve to shift and open said exhaust passage, means providing an ejector cooperating with said second mentioned surface, and said ejector being constantly supplied with motive fluid and discharging into said cylinder through a port overrun by said hammer, whereby said ejector is effective to subject said second mentioned surface of said valve to suction in one position of said valve and said surface is subjected to positive pressure when the discharge of said ejector is interrupted.

15. In a pneumatic hammer having in combination a cylinder, a hammer, a valve, said valve having working pressure surfaces effective to move the valve in opposite directions, a port overrun by said hammer for conducting actuating fluid from said cylinder for acting on one of said pressure surfaces and initiating movement of said valve in one direction, said port being in constant communication with the space adjacent said surface, means responsive to the movement so initiated for admitting live actuating fluid for acting on said area, and means for subjecting another area to suction upon completion of said movement of said valve.

16. In a pneumatic hammer having in combination a cylinder, a hammer, a valve, said valve having working pressure surfaces effective to move the valve in opposite directions, a port overrun by said hammer for conducting actuating fluid from said cylinder for acting on one of said pressure surfaces and initiating movement of said valve in one direction, said port being in constant communication with the space adjacent said surface, means responsive to the movement so initiated for admitting live actuating fluid for acting on said area, means for subjecting another area to suction upon completion of said movement of said valve, and means controlled by said hammer for converting said suction to positive pressure for moving said valve in the opposite direction.

17. A pneumatic hammer having in combination a cylinder, a hammer, a valve, said valve having working pressure surfaces effective to move the valve in opposite directions, conduit means constantly supplied with live motive fluid for admitting live motive fluid to one of said pressure surfaces when said valve is moved in one direction, a port overrun by said hammer for conducting actuating fluid from said cylinder for so moving said valve, and means for subjecting

- another pressure area to suction after completion of movement of said valve.
18. A pneumatic hammer having in combination a cylinder, a hammer, a valve, said valve having working pressure surfaces effective to move said valve in opposite directions, a port overrun by said hammer for conducting actuating fluid from said cylinder to one of said pressure surfaces for moving said valve, means responsive to such movement for subjecting one of said pressure surfaces to live motive fluid and another of said surfaces to suction.
19. A pneumatic hammer having in combination a cylinder, a hammer, a valve, means for moving said valve in one direction by actuating fluid from said cylinder and for holding said valve when so moved by live motive fluid and suction.
20. A pneumatic hammer having in combination a cylinder, a hammer, a valve, means for moving said valve in one direction by actuating fluid from said cylinder and for holding said valve when so moved by live motive fluid and suction, and means for changing said suction to positive pressure for moving said valve in the opposite direction.
21. A pneumatic hammer having in combination a cylinder, a hammer, a valve, means for conducting motive fluid and allowing it to act upon a pressure surface of said valve for shifting said valve, a port opened in response to movement of said valve for admitting motive fluid and allowing it to act upon said pressure surface after said valve is shifted, and a storage reservoir for the motive fluid supplied by said port, said reservoir being formed in said pneumatic hammer and being connected to the source of motive fluid supply for said pneumatic hammer by conduit means comprising a restricted passage.
22. A pneumatic hammer having in combination a cylinder, a hammer, a valve, a port overrun by said hammer for conducting actuating fluid from said cylinder and allowing it to act upon a pressure surface of said valve for shifting said valve, a storage reservoir formed in said pneumatic hammer having a restricted communication with the source of motive fluid supply for said pneumatic hammer, and means including a port opened in response to movement of said valve for conducting motive fluid from said storage reservoir and allowing it to act to lock said valve after said valve shifts.
23. A pneumatic hammer having in combination a cylinder, a hammer, a controlling valve, said valve having a forwardly acting working pressure surface and a rearwardly acting working pressure surface, means for conducting actuating fluid from the cylinder and allowing it to act on one of said pressure surfaces of said valve for shifting said valve, means responsive to movement of said valve for admitting air to the same pressure surface for locking said valve when shifted, and means for creating suction on the other of said pressure surfaces when said valve has been shifted.
24. A pneumatic hammer having in combination a cylinder, a hammer, a controlling valve, said valve having a forwardly acting working pressure surface and a rearwardly acting working pressure surface, means for conducting actuating fluid from the cylinder and allowing it to act on one of said pressure surfaces of said valve for shifting said valve, means responsive to movement of said valve for admitting air to the same pressure surface for locking said valve when shifted, means for creating suction on the other of said pressure surfaces when said valve has been shifted, and means for subjecting said last named pressure surface to positive pressure for again shifting said valve.
25. A pneumatic hammer having in combination a cylinder, a hammer and a controlling valve, said valve having a forwardly acting working pressure surface and a rearwardly acting working pressure surface, and means for subjecting one of said surfaces to pressure fluid at high pressure for shifting said valve and the other to suction for locking said valve when shifted and for subjecting the latter pressure surface to positive pressure for overcoming the pressure on the first acting surface for again shifting said valve.
26. A pneumatic hammer having in combination a cylinder, a hammer and a controlling valve, said valve having a forwardly acting working pressure surface and a rearwardly acting working pressure surface, means for subjecting one of said surfaces to pressure fluid at high pressure for shifting said valve and to pressure fluid at low pressure when shifted, means for subjecting the other of said surfaces to suction when said valve is so shifted and for subjecting the latter pressure surface to positive pressure for overcoming the effect of the pressure fluid at low pressure acting on said first acting surface when said valve is to be again shifted.
27. A pneumatic hammer having in combination a cylinder, a hammer and a controlling valve, said valve having two opposed working pressure surfaces, means for admitting air for acting on one of said surfaces and for simultaneously creating suction by ejector action on the other of said surfaces, and said means exhausting to the atmosphere by way of the bore of said cylinder both the air admitted to the first mentioned surface and the air for creating said suction.
28. A pneumatic hammer having in com-

bination a cylinder, a hammer and a controlling valve, said valve having opposed pressure surfaces, a port overrun by said hammer for conducting air from the bore of
5 said cylinder to one of said surfaces for moving said valve, means for supplying live air to said surface when said valve is so moved, means for subjecting the other of

said surfaces to suction by ejector action when said valve is so moved, and said last 10 named means exhausting to the atmosphere by way of the bore of said cylinder.

In testimony whereof, I have signed my name to this specification.

ERNEST H. SHAFF.

Certificate of Correction.

It is hereby certified that in Letters Patent No. 1,579,404, granted April 6, 1926, upon the application of Ernest H. Shaff, of Grand Haven, Michigan, for an improvement in "Fluid-Pressure Motors," an error appears in the printed specification requiring correction as follows: Page 3, line 55, claim 2, after the word "hammer" insert the words *piston, said valve*; and that the said Letters Patent should be read with this correction therein that the same may conform to the record of the case in the Patent Office.

Signed and sealed this 11th day of May, A. D. 1926.

[SEAL.]

M. J. MOORE,
Acting Commissioner of Patents.
